UNITED STATES PATENT OFFICE.

WILLIAM HENRY BEEHLER, OF BALTIMORE, MARYLAND.

DETACHABLE FASTENING FOR UMBRELLAS AND THE LIKE.

1,397,159.

Specification of Letters Patent. Patented Nov. 15, 1921.

Application filed August 6, 1914, Serial No. 855,422. Renewed February 16, 1918. Serial No. 217,711.

To all whom it may concern:

Be it known that I, WILLIAM HENRY BEEHLER, a citizen of the United States, residing at Baltimore, Maryland, have invented certain new and useful Improvements in Detachable Fastenings for Umbrellas and the like, of which the following is a specification.

The invention is especially useful in connection with detachable handles, but may in some cases be used for other separable parts of an umbrella frame or the like. Among the objects of the invention are to provide a strong and durable fastening which will 10 resist longitudinal strains as well as lateral or rotary strains; to secure the two parts together without lost motion; to provide ample dimensions in the head or latch proper and to so design the parts of the 15 device that it can be advantageously manufactured from stock of commercial size. The parts of an umbrella rod as now made are of exceedingly small diameter and it is a very difficult problem to combine with tubular parts of such small dimensions a detachable fastening of suitable characteristics. I 20 obtain the desired results, as will appear later, largely by taking advantage of the thickness of one of the tubular parts, for example by slotting it and permitting certain parts of the spring or spring-securing 25 devices to extend through these slots.

The characteristics and advantages of the invention can best be understood in connection with an explanation of the accompanying drawings which show exemplifying embodiments of the invention. It is to be understood that the invention is capable of embodiment in many forms and I do not limit 30 myself to details except as claimed herein- 35 after.

Figure 1 is an enlarged longitudinal section of adjacent parts of an umbrella rod and handle end showing a preferred form 40 of the invention.

Fig. 2 is a section at 2—2, Fig. 1.

Fig. 3 is a section at 3—3, Fig. 1.

Fig. 4 is a section at 4—4, Fig. 1.

Fig. 5 is a section at 5—5, Fig. 1.

Fig. 6 is a top plan of the dowel, of Fig. 1 with spring and spring fastening, other parts being removed.

Fig. 7 is a detail showing the method of inserting the spring.

Fig. 8 is an enlarged detail of the handle

end, showing the natural size of the dowel and spring head or latch.

Fig. 9 is a longitudinal section of another form of the invention.

Fig. 10 is a section at 10—10, Fig. 9.

60

Fig. 11 is a section at 11, Fig. 9.

Fig. 12 is a section at 12, Fig. 9.

Fig. 13 is a detail showing the method of inserting the spring.

Fig. 14 is a top plan of the dowel and 65 spring, other parts removed.

Referring first to Fig. 1, reference character 1 designates a tubular umbrella rod provided with a latch slot 2. The handle 3 is provided with a tube 4, usually of identical material with the rod 1 and of the same dimensions. In this tube 4, which may be termed the handle tube, is the dowel 5, usually also tubular, as shown, and extending within the end of the rod a suitable distance to provide transverse strength and prevent looseness, and so on. Within the dowel is the spring 6 having preferably a straight, or approximately straight, shank and terminating at its outer end in a head 75 or latch 7, which may be made of ample vertical dimension so that the latch face 8 will extend sufficiently through both the dowel tube and rod 1, to provide a very effective fastening. The upper corner of the 80 latch face 8 is usually rounded as at 9, to facilitate withdrawal of the dowel and latch, and the face 8 may preferably be made at a slight angle to the vertical, as shown, to tightly draw rod 1 and tube 4 together. The 85 dowel is provided with a slot 10 to accommodate the latch. Near the opposite end the spring shank is provided with a lug 11 engaging a hole 12 punched for it in the dowel. The engagement of this lug with a socket in 90 the dowel positively fixes the position of the latch face 8 in regard to the end of tube 4, and this, in connection with the accurate formation of latch slot 2 in the rod, so that its end 2a is the proper distance from the 95 end of the rod abutting against tube 4, serves to positively locate the end of the rod 1 against the end of tube 4 and prevent any rattling or lost motion. The spring is held in position by a device which may be termed 100 a "holding-piece" 13. This has a wide end 14, the upper side 15 of which rests in a slot 16 in the rear end of the dowel. The holding-piece also has a long, narrow extension 16', the lower edge of which rests in a 105

110

- slot 17 in the dowel and the upper edge of which, 18, underlies the lower edge of the rear end of the spring shank. When the metal parts are in the position shown in Fig. 1, but before tube 4 is inserted in the handle 3, the tube and dowel parts are locked together by drilling through the tube 4, dowel 5, and holding piece 13, and inserting a rivet 19.
- 10 It has been said that the head 7 or latch is of large dimensions, and it will be noticed that in making it of satisfactorily large dimension, especially in the vertical direction, it is larger than the inner diameter of 15 the dowel. It will also be noticed that the holding piece 13, in order to make it of suitable size and form, has a part of larger dimension than the inner diameter of the dowel. This being so, it would be impossible to assemble 20 the structure if the holding piece and spring were integral and it would also be impossible to insert the latch or holding piece by passing them through the bore of the dowel tube. To preserve the desired characteristics 25 of the latch, spring and holding devices, the spring and holding piece are made separate and the spring is inserted by passing its smaller end through dowel slot 10 as shown in Fig. 7, the spring shank being bent more 30 or less for this purpose but resuming its normal shape after insertion. When the spring is in proper position with its lug 11 in socket 12, the holding piece 13 is put in approximately the relative position shown in 35 Fig. 1; but a slight curvature of the spring shank or looseness of the parts, or other reasons, will usually cause the lower edge of the holding piece to project somewhat beyond the outer diameter of the dowel tube. The 40 dowel with its contained parts is then inserted in handle tube 4, the inner diameter of which closely approximates the outer diameter of the dowel tube, this insertion being usually made with a press or the like. The handle tube thus forces the holding piece 13 into place and holds all the parts in proper 45 relative position. The rivet 19 is then inserted as previously described and handle tube 4 inserted in a suitable handle.
- 50 Fig. 9 shows another form of the invention which obviates the difficulties in previous structures, although it is not so desirable for some reasons as the structure of Fig. 1. In this construction the spring is an integral 55 structure having a shank 20 with hub or latch 21 at one end and an enlarged butt 22 at the other end. This butt or spring-base has a lower edge 23 extending through a slot 24 in the end of the dowel tube, and at the opposite side the spring-base has a lug 25 extending through a socket 26 in the opposite wall of the tube. The vertical dimension 60 of the latch head is as large as will permit it to pass through the dowel tube and the head 65 is inserted from the rear end, as shown in

Fig. 13, and by somewhat springing the shank 20 the head will come into position in the dowel slot 10 and the butt or base 22 will come into position with its lower edge 23 in slot 24 and lug 25 in socket 26, as shown. 70 The handle tube 4 is then forced into position over the dowel tube firmly securing the spring in position, and all the parts are then permanently locked by drilling, and inserting rivet 27. On account of the method of 75 assembly, head 21 must be made as small as the inner diameter of the dowel tube. In this structure the spring is not subject to permanent deformation, resulting in loosening of the handle tube and rod in relation to each 80 other. For some reasons, however, largely manufacturing considerations, the form shown in Fig. 1 is more practical and advantageous.

Fig. 8 shows the natural size of the handle 85 tube 4 and dowel 5. The rod stock is usually of steel in a standard mill size, and this standard size must be used both to conform with the demand for umbrella rods of small 90 size and to secure the rod stock at a commercial price. Much difficulty is encountered in adapting fastening parts to these small tubes and the present structures, adapted to the standard tube size, have been developed after 95 long experimentation and practical tests. It will be noticed that in order to produce satisfactory results, every fractional inch of available space must be used at some point or other of the tube. Even by utilizing all possible room the fastening parts are reduced 100 probably to the smallest dimensions which will give necessary strength and spring action. Reference to the transverse-sectional figures, such as 2 to 5 inclusive, demonstrates what would not ordinarily be apparent—that even the full inside diameters of the tubes cannot be used in practical constructions, because the necessary thickness of the spring parts and the fact that they must be produced economically by punching, with 105 squared edges, causes the edges of the spring parts and fastening parts, as 6, 13 (Fig. 1) to occupy within the tubes the place of chords of the circle formed by the inner surface of the handle tube 4, the distance from chord to 110 chord through the center being, of course, appreciably less than the actual diameter of the tube. When it is remembered that the inside diameter of this tube is only .222", the rigid limitations within which the disclosed 115 structures were produced and the necessary 120 study and care for their production will be appreciated.

The standard umbrella rod used is size 4 $\frac{1}{2}$, having outside diameter of .282" in a 125 wall $\frac{1}{2}$ " thick. This leaves the bore or inside diameter of the tube .222". The dowel to fit this diameter must be approximately .220", allowing a variation of .002" to permit insertion of the dowel. The rods are 130

reamed to vary from .222" to .224". The dowel tube has an outside diameter, therefore, approximately within the limits .218" to .222" outside diameter and varies from .150" to .160". This leaves only .150" to .160" working space in which to place a spring which must lock two tubes together, the wall of each of which measures .031 and having a total variation in thickness of .012".

I claim:—

1. In an umbrella or the like, the combination of a tubular rod having a latch slot, a handle tube abutting against the rod, a dowel permanently fixed in the handle tube and having the protruding part removably inserted in the rod, a spring within the dowel having a latch head extending through the dowel wall to engage said latch slot and also having a lug entering an aperture formed in the dowel wall, a holding piece engaging slots in the dowel wall and also engaging the spring to lock it in position, said holding piece also engaging the inner surface of the handle tube whereby the dowel, spring and holding piece are mutually locked securely in position.

2. In an umbrella or the like, the combination of a slotted tubular rod, a handle tube, a dowel seated within the handle tube and removably entering the rod, a spring within the dowel having a latch head passing through the dowel and engaging the rod slot, and a fastening member for the spring extending across the dowel and having at one edge a lug engaging the dowel wall and opposite said lug having a long edge extending through a slot in the dowel and engaging the inner surface of the handle tube.

3. In an umbrella or the like, the combination of a hollow rod having a latch slot, a handle tube, a dowel permanently seated in the handle tube and having an extension removably entering the rod, a spring having an approximately straight shank located within the dowel near one side thereof and having a head extending through the wall of the dowel and engaging said latch slot, said spring also having a lug engaging a socket in the dowel wall

near one end of said shank and a holding piece separate from the spring having an end substantially equal to the diameter of the dowel and extending through opposite slots in the dowel wall and engaging the inner surface of the handle tube, said holding piece also having an extension, one edge of which engages the spring shank to hold the spring in position and the other edge of which lies in one of said slots in the dowel and engages with the inner surface of the handle-tube.

4. In a detachable handle for umbrellas and the like, the combination of a tubular dowel having a latch slot on one side and a spring latch having an approximately straight shank and a latch head substantially as deep in the plane of the latch slot at least as the inner diameter of the dowel tube, the dimension of the shank in the same plane adjacent to the latch head being relatively small to permit the latch head to protrude amply through the latch slot, a holding device at the end of the shank remote from the latch head, the dimension of said device in the above mentioned plane being greater than the inside diameter of the dowel tube, the tube being provided with substantially opposite openings to receive portions of said holding device, and a handle tube closely fitting outside the dowel tube and secure to it to lock the other parts in position.

5. In a detachable handle for umbrellas and the like, the combination of a tubular dowel having a latch slot, a latch having a relatively long and narrow and approximately straight shank and a head dimensioned to extend well outward through the latch slot, the shank being provided with a projection at one edge near the end remote from the head, and a separate holding piece inserted within the end of the dowel tube and engaging the latch, and co-operating with the latch shank and projection to lock the latch in position in the tube.
